(57) **CLAIM**

The ornamental design for a wastewater pipe, as shown and described.

DESCRIPTION

FIG. 1 shows a front perspective view of a wastewater pipe; FIG. 2 shows a front elevation view of the wastewater pipe of FIG. 1;

FIG. 3 shows a right elevation view of the wastewater pipe of FIG. 1 with the left elevation view being the mirror image of the right elevation view;

FIG. 4 shows a top elevation view of the wastewater pipe of FIG. 1;

FIG. 5 shows a rear elevation view of the wastewater pipe of FIG. 1; and,

FIG. 6 shows a bottom view of the wastewater pipe of FIG. 1. The broken line showing is included for the purpose of illustrating portions of the article and forms no part of the claimed design.
